UNITED STATES PATENT OFFICE.

WALLACE J. BISSET, OF BLOOMSBURG, AND MORRIS S. EVANS, OF BERWICK, PENNSYLVANIA, ASSIGNORS TO AMERICAN CAR AND FOUNDRY COMPANY, OF NEW YORK, N. Y., A CORPORATION OF NEW JERSEY.

ELECTRIC HEATER.

Application filed June 19, 1922. Serial No. 569,237.

To all whom it may concern:

Be it known that we, WALLACE J. BISSET and MORRIS S. EVANS, residing at Bloomsburg, Columbia County, Pennsylvania, and Berwick, Columbia County, Pennsylvania, respectively, and being citizens of the United States, have invented certain new and useful Improvements in an Electric Heater, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a side elevation of our improved heater;

Fig. 2 is a front elevation of our improved heater, parts being broken away to show other parts more clearly;

Fig. 3 is a plan view of the movable stops, detached from the rest of the heater structure;

Fig. 4 is a side elevation of a modified form of our device;

Fig. 5 is a front elevation of the structure shown in Fig. 4; and

Fig. 6 is a top plan view, drawn to a larger scale of the structure shown in Fig. 4.

It is an object of our invention to provide an improved electric heater which shall be capable of heating stock of different lengths and it is also an object of our invention to provide means by which the electrodes may be readily adjusted to accommodate the different lengths of stock. It is also an object of our invention to provide an improved operating means for the electrodes and it is also an object of our invention to provide a heater in which current from two sources is used to heat the stock. It is also an object of our invention to provide an improved means for feeding the stock to the electrodes.

With these and other objects in view, our invention, as shown in Figs. 1 and 2 comprises an electrical heater having a support-

ing frame composed of spaced flanged side members 1 and 2, of irregular shape, joined by cross members 3 secured to the flanges of the members 1 and 2. The side members may be formed in any desired manner but we have shown them as cast members formed with integral flange portions 4 and 5, respectively, upon which is mounted a channel-shaped cross member or support 6. The member 6 is provided with a row of openings 7 and serves to support a pair of electrodes 8 and 9 which rest upon insulation 10 and are secured to the support 6 by the bolts 11, also insulated from the support 6, which pass through the openings 7. The row of openings 7 serves as a means for positioning the electrodes 8 and 9 so as to accommodate stock of any length up to the limit of the apparatus.

Cooperating with the electrodes 8 and 9, respectively, are the electrodes 12 and 13. The electrodes are supported by rods 14 connected by insulating couplings 15 to sleeves 16 slidably mounted upon a rod 17 and held in adjusted positions upon the rod by set screws 18. The rod 17 is carried by sleeves or boxes 19 slidably mounted in slots 20 in the side members 1 and 2 and normally forced to their lowermost position by springs 21, the force of which may be adjusted by adjusting screws 22 mounted in brackets 23 which close the upper ends of the slots 20.

To operate the rod 17 and boxes 19 in the slots 20 there is provided at each end of the heater, a lever 24 pivotally supported by the adjacent side member as at 25 and pivotally connected, intermediate its ends, to a link 26 which has its other end pivotally connected to an end of a lever 27. The lever 27 is mounted on a shaft 28 carried by the side members 1 and 2 and has its other end rounded, as at 29, and engaging a roller 30 mounted upon the rod 17. To permit of adjusting its length, the link 26 is formed of sections joined by a turnbuckle 31. Surrounding the rod 26 is a spring 32 which is confined between a collar 33 fixed on the rod and a bracket 34 formed integral with the side member and through which the rod 26 passes. Connecting the levers 24 is a rod 35 which is engaged by the operator to operate the levers 24.

The side members 1 and 2 are also pro-

vided with inclined flanges 36 and 37 upon which is mounted a support 38 for supporting the stock to be heated, shown in Figs. 1 and 2 as round bars 39. In order 5 to hold the bars 39 on the support 38 and to feed them to the electrodes one at a time, movable stops 40 and 41, adapted to project through openings in the support 38, are provided. The stops are movably mounted 10 in a guide bracket 42 formed integral with the support 38 and are provided with racks 43 and 44, respectively, which engage opposite sides of a pinion 45 so that operation of the pinion 45 will cause one stop to be 15 drawn below the upper surface of the support 38 and the other stop to be projected above the support. Reversing the operation of the pinion 45 will reverse the positions of the stops. It will be noted that the stops 20 40 and 41 are spaced apart so that when stop 40 is retracted and stop 41 projected the rods 39 roll down the support 38 and engage the stop 41. When the stop 40 is projected and the stop 41 retracted, the stop 25 40 will be forced between the two lowermost bars so that all bars but the lowermost bar will be held by the stop 40 while the retraction of the stop 41 will release the lowermost bar and permit it to roll down the 30 support 38 to the electrodes.

The pinion 45 is mounted upon a shaft 46 journaled in the side members 1 and 2. While we have shown but one pinion 45 on the shaft 46 it is to be understood that a 35 plurality of pinions 45 may be operated by the one shaft 46 and operate pairs of stops, spaced as desired, across the machine. The shaft 46 is operated by cranks 47 mounted upon the ends of the shaft 46 and connected 40 by adjustable links 48 to the ends of levers 49 which are pivotally mounted, intermediate their ends, as at 50, upon the side members 1 and 2. Links 51, which pass through brackets 52 and are provided with 45 yoke-shaped ends having pin and slot connections with levers 24, operatively connect the other ends of the levers 49 to the levers 24. Springs 53, which surround the links 51 and are confined between the brackets 52 and collars 54 secured on the links 51, are adapted to return the stops 40 and 41 to 50 their normal positions.

To stop the rods in position on the electrodes 8 and 9 after they have been released 55 by the retraction of the stop 41, stops 55 are provided. The stops 55 are mounted upon rods 56 to which they are connected by insulating connectors 57. The rods 56 are guided in openings in the support 6 and 60 are connected to cranks 58 mounted on a shaft 59 journaled in the side members 1 and 2. Cranks 60 mounted on the ends of the shaft 59 connect the shaft 59 to the links 51.

65 In the operation of our device when

constructed as described above, pressing down the cross bar 35 will operate levers 24, links 26 and levers 27 to raise the rod 17 against the action of springs 21 and 32 and raise the electrodes 12 and 13, the pins 61 traveling in the slots 62 in the ends 63 of the links 51 until the pins 61 engage the bottoms of the slots, the slots 62 being of sufficient width to permit the movement of the pin 61, whereupon the links 51 will be operated against the action of springs 53, operating cranks 60 to withdraw the stops 55 and permitting the bar 39, if any, held upon the electrodes 8 and 9 to roll down the electrodes and be received upon the support 6. 70 The rods 39 are held on the support 6 by the projecting portions 64 of the side members 1 and 2 or by projections which may be provided on member 6. The operation of the links 51 also operates the lever 49, link 48 and crank 47, operating the pinion 45 and withdrawing the stop 40 and projecting the stop 41 thus allowing the bars 39 to advance to engage the stop 41. When the pressure upon the rod 35 is removed and the 75 rod allowed to return, the stops 55 will be projected into position to hold the bars upon the electrodes 8 and 9 and the stop 40 is projected between the two lowermost bars, holding all save the lowermost bar while the 80 stop 41 is withdrawn and the lowermost bar released to roll down the support 38 on to the electrodes 8 and 9 and engage the stops 55. The stops 40, 41 and 55 are restored to their normal positions before the levers 24 85 so that there is an opportunity for the rods 39 to pass on to the electrodes 8 and 9 and engage the stops 55 before the electrodes 12 and 13 descend and engage the bar. Current for heating the bars is supplied to the 90 electrodes through flexible conductors 65, the source of current supply being such that the current will pass through the bar from end to end in two paths, one path being from electrode 8 to electrode 9 and the 95 other path being from electrode 12 to electrode 13, the source of supply for the electrodes 8 and 9 being so arranged that it may or may not be separate from the source of supply for electrodes 12 and 13. 100

In the modified construction of our device shown in Figs. 4, 5 and 6, the structure comprises pressed flanged base members 70 and 71 having their bottom flanges connected by an angle bar 72. To the base members 70 and 71, respectively, are secured the spaced vertically projecting angle bars 73, 74 and 75, 76, each angle bar having one flange secured to the adjacent base member and one flange cut away so as to rest upon the 105 base member and all the bars being arranged, as shown in Fig. 6, so that they will embrace the vertical edges of the rectangular laminated core 77 of a transformer 78. Engaging the angle bars 73, 74, 75 and 76 are 110 115 120 125 130

the filler members 79 which are held in position by bolts 80 and 81 which pass through openings in the filler members and angle bars below and above the core, respectively, and 5 also serve to hold the angle bars tightly against the cover plates 82 which are placed between the sides of the core 77 and the angle bars. Bolts 83, passing below the core 77 hold the lower portions of the plates 10 against the core. On the upper surface of the core 77 is placed insulation 84 upon which rest the spaced primary coils 85 of the transformer 78. Between the coils 85 are placed the secondary coils 86 and 15 87, insulating separators 88 being placed between each secondary coil and the adjacent primary coil.

The electrode 89 of the secondary coil 86 is adjustably supported by an insulated 20 bolt 90 from a strap 91 which is connected to the filler members 79 by the bolts 81 while the other electrode 92 of the coil 86 is adjustably supported by an insulated bolt 93 from a strap 94 secured to the filler members 25 79. The bolt 93 engages the coil 86 a short distance below the electrode 92 while the electrode 92 is yieldingly connected to an insulated strap 95, carried by the filler members 79, by a bolt 96 slidably mounted in an opening in the strap 95 and carrying a spring 97 confined between the strap 95 and a nut 98 on the bolt 96. This construction 30 permits the electrode 92, which is normally inclined, to move slightly when subjected to pressure, the inclination being too slight to be clearly shown in the drawing. The electrodes 99 and 100 of the secondary coil 87 are connected by insulating connectors 101 to sleeves 102 slidably mounted on a 35 rod 103 and normally held in fixed positions on the rod by set screws 104. The rod 103 is mounted in blocks 105 slidably mounted in slots 106 in guide members 107 secured to the filler members 79 by bolts 108. The 40 blocks 105 are pressed to their lowermost positions by springs 109, the force of which is regulated by adjusting screws 110 mounted in brackets 111 which close the open ends of the slots 106. On the ends of the rod 45 103 are mounted rollers 112 engaged by cams 113 mounted on a shaft 114 journaled in the guide members 107 and having mounted thereon a crank 115 which is connected by a link 116 to one end of a lever 117. The 50 lever 117 is pivotally mounted in a bracket 118 carried by the angle bar 72 and has a pedal 119 pivotally connected to its other end.

It will be noted that the contact of the 60 electrodes 89 and 92 with the object to be heated will complete the circuit through the secondary coil 86 and that contact of the electrodes 99 and 100 with the object will complete the circuit through the secondary coil 87, the circuits of the secondary coils

having only the object to be heated in common.

Connecting the electrodes 89 and 92 to one secondary coil and the electrodes 99 and 100 to another secondary coil permits of 70 the use of secondary coils of less current carrying capacity than where all the electrodes are connected to one secondary coil and the secondary coils are in consequence much more readily manufactured and re- 75 paired. It also causes the load to be applied in two (2) steps as the pairs of electrodes are brought into contact with the work piece and reduces the tendency to arcing at the electrodes. 80

In the operation of the device shown in Figs. 4, 5 and 6 depressing of the pedal 119 will operate the lever 117 and cams 113 to raise the electrodes 99 and 100 against the action of springs 109 to permit the insertion and removal of the stock and removal of the pressure from the pedal will permit the springs 109 to force the electrodes 99 and 100 into engagement with the stock and to hold the stock in contact with the electrodes 89 and 92. 85

It will be apparent that the source of current for the device shown in Figs. 1, 2 and 3 may be similar to the transformer shown in Figs. 4, 5 and 6 and that the transformer may be mounted on the machine frame or placed on the floor near the machine. 90

What we claim is:

1. In an electric heater, normally fixed electrodes adapted to complete a circuit upon engagement by the stock, movable electrodes cooperating with said fixed electrodes and adapted to complete a second circuit upon engagement with the work and means adapted to operate said movable electrodes to make and break said second circuit. 100

2. In an electric heater, normally fixed electrodes adjustable horizontally and adapted to complete a circuit upon engagement by the stock, movable electrodes adjustable horizontally to cooperate with said fixed electrodes and adapted to complete a second circuit upon engagement with the work and means adapted to operate said movable electrodes to make and break said second circuit. 110

3. In an electric heater, a movable support, electrodes of one circuit normally fixed on said support, electrodes of a second circuit normally fixed in position and adapted to cooperate with the first mentioned electrodes and operating means for said support adapted to hold said electrodes in engagement with the stock heated. 115

4. In an electric heater, cooperating fixed and movable electrodes, stock feeding means and stops adapted to position the stock on said fixed electrodes. 125

5. In an electric heater, cooperating fixed and movable electrodes, stops adapted to 130

- hold the stock on said fixed electrodes and operating means for said movable electrodes adapted to operate said stops to release the stock from the fixed electrodes.
- 5 6. In an electric heater, cooperating fixed and movable electrodes, means adapted to feed stock to said fixed electrodes and operating means for said movable electrodes adapted to operate said stock feeding means.
- 10 7. In an electric heater, cooperating fixed and movable electrodes, means adapted to feed stock to said fixed electrodes, stops adapted to position the stock on said fixed electrodes and operating means for said movable electrodes adapted to operate said stock feeding means and said stops.
- 15 8. In an electric heater, cooperating fixed and movable electrodes, means adapted to feed stock to said fixed electrodes, stops adapted to position the stock on said fixed electrodes, an operating means for said movable electrodes and an operating means for said stock feeding means and said stops having a lost motion connection with said electrode operating means.
- 20 9. In an electric heater, cooperating fixed and movable electrodes, inclined stock supporting means, stock feeding means adapted to release the stock on said supporting means upon operation of said movable electrodes
- and stops adapted to position the stock on said fixed electrodes.
10. In an electric heater, cooperating fixed and movable electrodes, means adapted to feed stock to said fixed electrodes, stops adapted to position the stock to complete a circuit through said fixed electrodes and means adapted to operate said movable electrodes to complete a second circuit through said work.
11. In an electric heater, cooperating fixed and movable electrodes and means for feeding stock to said fixed electrodes comprising a stop normally engaging the stock and adapted to release the stock and a second stop adapted to engage the stock upon movement of said movable electrodes from said fixed electrodes, said first stop being adapted to engage and hold some of the stock and said second stop being adapted to release the remainder of the stock upon movement of said movable electrodes toward said fixed electrodes.

In witness whereof we have hereunto set our hands in the presence of two witnesses.

WALLACE J. BISSET.
MORRIS S. EVANS.
